WEB TENSION CONTROL FOR PRINTING
PRESSES

Kenneth G. Laycock, Shavertown, Pa.

Application November 4, 1950, Serial No. 194,142

12 Claims. (Cl. 242—75)

1

The present invention has for its object the provision of a novel and improved tension mechanism for controlling the tension of web fed from a web roll to a printing press.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a schematic side elevation, partly in section of a typical and preferred, illustrative embodiment of the present invention; and

Figures 2, 3, 4 and 5 are detailed vertical sections taken on the lines 2—2, 3—3, 4—4 and 5—5, respectively, of Figure 1.

The present invention has for its object the provision of a novel and improved web tension mechanism for printing presses which produces a more uniform control of the web tension than has heretofore been attained by the mechanisms generally used for this purpose. A further object is the provision of an improved mechanism for controlling the tension of a web by means of moving belts or other driven friction members in frictional contact with the web supply roll, so as to maintain a constant tension on the running web and at the same time to slow or stop the web roll as the press slows down or as a break occurs in the web. The invention further provides a simplified form of web tension mechanism which requires no complex or separate source of power for its actuation and which is completely reliable in its operation.

The present invention provides an improved web tension mechanism which is of the general type disclosed in the patent to Stone, 1,722,508 of 1929, but which provided no variable control for the friction exerted on the web supply roll.

According to the present invention, one or more web supply rolls are supported for rotation so that successive web rolls may be brought into web feeding position and the active web roll is engaged by a set of slowly moving belts, spaced across the width of the roll and pressed into and

2

maintained in firm frictional contact with the surface of the active web roll so that the difference in speed between the belts and the surface of the web roll exerts a regulable drag on the roll

5 to create the desired tension in the web fed to the printing press. The friction belts are preferably driven from and proportionally to the speed of the press and are also subject to the action of brake mechanism which serves to regulate the pressure between the belts and the web roll. The belts each pass over two pulleys, one of which is a driving pulley and the other of which is a brake pulley so that the constant driving of each belt maintains contact with the web roll while the pressure of this contact is regulated by the effort exerted on the belt by the brake mechanism.

For maintaining the web tension constant by variation of the belt-braking effort, the web

20 passes over a pilot roller on its way to the press, the pilot roller being substantially counterbalanced so that it may be readily moved by changes in the web tension. Included in the counterbalancing means, and for opposing the action of the web tension on the pilot roller is a resiliently supported large mass which exerts a steady force on the pilot roller and is so resiliently suspended that minor and sudden movements of the pilot roller cause substantially no movement of the mass. Thus, the mass is moved only by continued or slow movements of the pilot roller, and the pilot roller may move much more rapidly than if a corresponding movement of the mass were necessary.

35 Means are also provided for allowing the mass to move more freely in one direction than the other so as to eliminate the possibility of continued oscillation of the pivotally and resiliently mounted pilot roller.

40 The brake means acting on the web roll engaging belts are interconnected so that the belts exert a substantially equal pressure on the web roll, and these brake means are preferably of the self-energizing or servo type so that a slight increase in the pressure applied to the brake causes a greater increase in the braking effort exerted by the brake.

45 The brake means are preferably interconnected with and controlled by the pilot roller so that the apparatus as a whole is controlled by the actual web tension and any increase or decrease in the web tension from the normal value causes a compensatory change in the braking force exerted on the belts and likewise a change in the drag exerted by the running belts on the web

roll, so as to maintain a constant web tension at the desired value.

It will be understood that the foregoing general description and the following detailed description as well are exemplary and explanatory of the invention but are not restrictive thereof.

Referring now in detail to the present preferred and illustrative embodiment of the invention, the tension mechanism is shown as applied to a conventional magazine reel 10 adapted to rotatably support an active web roll 12 from which a web of paper 14 is fed to the printing press (not shown), reserve web rolls 16 of paper being supported by the reel 10 so they may be brought successively into web feeding position by rotation of the web reel 10 about its shaft 18 fixed in the press frame 20.

In being fed to the press, the web 14 passes over guide rollers 22 and is looped around a pivotally mounted pilot roller 24, the position of the pilot roller being determined by the tension of the web drawn from the web roll 12.

Rotation of the active web roll 12 is opposed and tension on the running web 14 is created by means of a plurality of similar endless belts 26 formed of friction material, such as fabric, the several belts being spaced apart longitudinally of the web roll, and being supported so that each normally makes arcuate contact with the web roll, and travel relatively slower than the surface of the web roll 12, thereby creating friction or drag, the amount of which depends on the pressure between the belts 26 and the web roll 12, the angular extent of the contact between them, and to a slight extent on the difference in speed between the belts and the surface of the active web roll.

As embodied, each of the belts 26 is supported by means of a pair of pulleys 28, 29 one above and one below the web roll 12 and so positioned that the reach of the belt 26 towards the web roll 12 will wrap the web roll 12 for a substantial arc whether the web roll is large or almost exhausted.

Cooperating with each of the pulleys 28, 29 are means for preventing slippage of the belt on the surface of the pulley and for this purpose a supplemental belt 30 is provided for firmly holding the friction belt 26 on the pulley, the supplemental belt 30 running freely over two idler pulleys 32 and a resiliently mounted slack take-up pulley 34, the pulleys 32 and 34 being positioned to provide a large wrapping contact between the belts 26 and 30.

The speed of running of the belts 26 is controlled by driving the belts from the printing press and for this purpose the pulleys 28 are all keyed to a shaft 40 which is journaled in the press frame 20 and is driven from the press through chain 41 and sprocket 42, the speed of driving being a small fraction of the press speed so that the belts 26 preferably have a surface speed of about 10% of the web speed.

The pressure of the belts 26 against the surface of the web roll is preferably controlled by means of a brake actuated by movement of the pilot roller in response to changes in web tension, the brake serving to exert a drag on the belts 26 as they are driven from the press. As embodied, each of the belts is provided with its individual brake means in the form of a brake drum 44 keyed to the corresponding belt pulley 29, so that, with the cooperation of the corresponding supplemental belt 30, the belt 26 is retarded to exert a variable pressure and drag on the web roll 12.

A deflector plate 27 is provided for the return reach of each belt 26 to guide the belts 26 and prevent the slack from fouling the belts, each of the deflector plates being mounted on a cross frame member 27'.

Each of the brake drums 44 and belt pulleys 29 is mounted for rotation on a shaft 46 which is supported in pairs of upright frame members 48, one such pair being provided for each belt 26 and in the frame 20 at the ends of the shaft 46.

Cooperating with each brake drum 44 is a pair of arcuate brake shoes 50, 51 mounted for movement toward and from the brake drum 44. Shoe 50 is carried by a plate 52 above the drum 44 while shoe 51 is mounted on the lower plate 53, the two plates being connected together by means of the pivotal link 55 so that the shoes 50, 51 may press against the drum 44. The other end of plate 52 has a normal position and braking pressure on the shoes is normally provided and maintained by means of resilient pressure on the other end of the lower plate 53, through spring 57 which is compressed between the end of the plate 53 and an end of the weighted bell crank 58 which is pivotally mounted for oscillation on shaft 46, and is limited in oscillation by stops 60 on an adjacent frame member 20 or 48. The weighted bell crank is normally held by the upper stop 60 and the brake is normally energized by the pressure exerted by spring 57 on the lower plate 53 of the brake, but the braking force can be greatly increased by rotation of the brake as a whole so that bell crank 58 engages the lower stop 60 and spring 57 is compressed more than normal. The normal braking force on each of the belts 26, and on the web roll may be varied by movement or replacement of the weight 62 on bell crank 58.

For controlling and varying the braking force and thereby regulating the tension of the web fed to the printing press, the pilot roller is connected to the brake mechanism by means of a flexible cable 66 which is preferably interconnected to the several brake mechanisms so as to equalize their action. As embodied, the cable 66 is fixed to a drum 67 on the shaft 68 by which the pilot roller 24 is pivotally mounted and is connected to one end of the brake shoe supporting plates 52 so that pivotal movement of the pilot roller 24 on decreasing tension of the web 14 causes the upper plate 52 to be pressed more powerfully against the brake drum 44.

Cable 66 passes over guide pulleys 72 and runs over pulley blocks 70 which are connected by cables 73 to the free end of each upper plate 52, while the end of cable 66 is anchored by means of a relatively heavy weight 74 which normally rests on the floor. The force thus applied through the pulley blocks 70 and cables 66 to the several braking means is equalized. The maximum braking force which can be applied is thus limited by the mass of weight 74 which is lifted from the floor on an extreme movement of the pilot roller 24.

Means are provided for substantially counter-balancing the pilot roller 24 on its pivotal mounting 68, and also for moving the pilot roller as the web tension slackens and for opposing movement of the pilot roller as the web tension increases. As embodied, pilot roller 24 is rotatably mounted at its ends in arms 80 which are keyed to the rotatable shaft 68, at least one of these arms extending to the other side of the shaft 68 so that it provides a mounting for counter-weight 82 which may be held in various radial positions by means of its set screw 84, thereby

providing a means for accurately counterbalancing the pilot roller 24 when the other forces acting on the roller are disregarded. For urging the pilot roller against the tension of the web at the pilot roller loop, a cable 86 extends downwardly and is fixed at its upper end to the pulley 67, fast on shaft 68. Cable 86 supports the relatively heavy masses 88 and 89 which correspond to the tension desired to be established on the web by the action of the friction belts 26 bearing against the running web roll 12. The masses 89 are preferably in the form of removable weights which can be removed or replaced to adjust the tension of the web to the desired value.

The tension creating masses 88 and 89 are resiliently supported from the cable 86, and such resilient support is preferably provided by means of a spring 90 interposed in the suspension systems between the cable 86 and the masses 88, 89. As shown, cable 86 is connected to a vertically extending guide rod 92 by means of yoke 94, guide rod 92 is guided in guide brackets 96 mounted on the side frame 20, and at its lower end, is pivotally connected to a lever arm 98 which is also pivotally connected to link 99 extending upwardly from the lever arm 100 which is pivotally connected to a guide rod 101 forming the mounting member for the masses 88 and 89. The link 99 is preferably adjustable toward and from the guide rods 92 and 101, and may be held in any desired position in lever 100 by tightening nut 102 so as to hold the link 99 in the desired position in the slotted end of lever 100 while the upper end of link 99 is variably pivoted by means of a pivot pin which may be inserted in any one of the holes 103. Positioned between the link 99 and the vertically aligned guide rods 92 and 101 is a link 104 pivoted at its lower end to the lever 100, and slidably in a bushing 105 which is pivoted to the upper lever 98. The upper end of the link 104 carries compression spring 90 which is variably compressed between the bushing 105 and nut 106, thereby providing a variably resilient suspension system for the masses 88, 89 so that minor and sudden movements in the position of the pilot roller 24 caused by quick changes in the web tension are absorbed without causing substantial movement of the masses 88 and 89.

Spring means are provided for limiting upward motion of the cable 86 and for this purpose a coil spring 108 is wound around the guide rod 92 and is supported on collar 109 serving as a resilient stop to engage the lower portion of guide bracket 96.

A similar resilient connection is provided in the flexible cable 66 so that movements of the pilot roller 24 are resiliently transmitted to the brake systems for the running belts 26. While this resilient connection may be a duplicate of that just described, it is preferably additionally provided with means for minutely adjusting the position of the link 99 with respect to the vertically extending rod 110 and cable end 111 which corresponds to the rods 92 and 101, respectively. The minute adjustment of link 99 is effected by means of a threaded member 112 provided with a hand wheel 114 rotatably mounted and held against axial movement by bracket 116, 70 with the threaded member engaged in a threaded aperture in link 99 so as to traverse the link with respect to the members 110 and 111. The lower end of the link 99 is freely slidable in a slot in the lower lever 100, while the upper 75 cause corresponding movements of the pilot roller

end of link 99 is provided with a pin 118 which is slidably supported in slot 120. The upper end of rod 110 is preferably connected to the upper portion of cable 66 by means of a turnbuckle so that the effective length of the cable 66 may be adjusted to provide the desired position of the pilot roller 24 for a normal setting of the brake.

Additional snubbing means are provided for 10 allowing the pilot roller 24 to move downwardly on decreasing tension more easily than it is allowed to move upwardly on increasing tension. For this purpose rod 101 is provided with a wedge shaped member 122 tapering upwardly, the sides 15 of the wedge engaging with friction pads 124 mounted on the inner ends of slide blocks 126 which are slidably mounted in guides 128 fixed to the side frame 20, the friction faces 124 being pressed inwardly into resilient engagement 20 with the wedge faces 122 by means of levers 130 pivotally mounted above the guides 128. The upper ends of levers 130 are provided with threaded members 132, the inner ends of which 25 compress springs 134 against the bracket 136 mounted on the side frame 20, thereby providing variable resilient pressure on the friction members 124 so that the degree of snubbing of the movement of the masses 88 and 89 may be controlled as desired.

In operation, the web is threaded from the web roll to the press to form a loop around the pilot roller 24. The pilot roller counterweight 82 is adjusted so that the pilot roller supporting arms 89 assume a substantially horizontal position. Sufficient weights 88 and 89 are used to provide 35 a downward pull on the pilot roller 24 which will normally equal the desired tension on the full web 14 as it is fed to the press. The rollers 34 are adjusted so that the belts 30 firmly hold 40 the running belts 26 against the pulleys on which they are mounted, and the springs 90 and 134 are adjusted to give the desired degree of resiliency, while weights 62 are positioned so as to create the desired braking force on the several 45 running belts 26.

The printing press is now placed in operation and the web is drawn from the active web roll 12 at the same time that the belts 26 are slowly driven from the press, the feeding of the belts 50 being opposed by the several brake shoes 50 and 51 so that the belts 26 are more or less freely engaged with the surface of the web roll 12 to oppose rotation of the web roll.

A gradual increase in the tension of the web causes pilot roller 24 to raise, thereby slackening the cable 66 and diminishing the pressure with which the brake shoes 50 and 51 are pressed toward each other and allowing the belts 26 to be fed more readily so that the pressure between them and the web roll 12 is diminished to allow the web roll to rotate more freely thereby re-establishing the original desired tension. At all times braking pressure between the brake shoes 53 and 51 is controlled by the force exerted by the weight 62 as transmitted through the spring 57 which controls the feed of the belts 26 and thereby the pressure of the belts on the web roll.

Irregularities in the running of the web rolls 12 are compensated for by the interconnection of the several brake mechanisms to the pulleys 70 and cable 66 so that a deformed or irregular roll can operate smoothly without creating sudden inequalities in the web tension.

Sudden minor variations in the web tension cause corresponding movements of the pilot roller

24. but if these variations are purely transient they are absorbed by movement of the pilot roller against the compression of the spring connections so that no substantial movement of the masses 88, 89 or of the brake cables 73 occurs. However, gradual changes in web tension are transmitted to the several brakes and the force usually applied to the cables 73 and the corresponding brakes is the force exerted from the masses 88 and 89. The wedge member 122 allows the brakes to be applied rapidly in case of an emergency shutdown of the press and also allows the masses 88 and 89 to move downwardly more easily than upwardly so that a gradual increase in the braking force exerted between the brake shoes 50 and 51 occurs, compensating for the reduced angle of the arcuate contact between the belts 26 and the web roll 12 which occurs as the web roll is used up. Any gradual increase in the web tension causes the pilot roller 24 to move upwardly thereby allowing the brake shoe 50 to move very slightly away from the brake shoe 51 so that the upper stop 60 prevents full application of the pressure created by weight 62 to force the brake shoes together and resulting in a reduction in the pressure between the belts 26 and the web roll 12 so that the web 14 is more easily fed from the web roll 12 thereby restoring the web tension to the desired normal value.

In the case of a web break or a sudden slowing or stoppage of the printing press, pilot roller 24 moves rapidly downwardly under the influence of weights 88, 89 tending to lift or actually lifting the weight 74 and causing each of the brakes to be rotated counterclockwise (Figure 1). As the brake shoes 50, 51 and their supporting members 52, 53 are so moved, bell crank 58 is likewise moved counterclockwise against the force of weight 62 and about shaft 46. In case great additional braking effort is called for, bell crank 58 moves sufficiently so as to be brought against the lower stop 60 thereby causing spring 57 to be further compressed and providing additional pressure on the brake shoes 50, 51 so as to cause a tightening of the belts 26 against the web roll 12 and an increased drag on the web roll which produces an increased web tension to slow or stop the running web roll.

The invention in its broader aspects is not limited to the specific mechanisms shown and described but departures may be made therefrom within the scope of the accompanying claims without departing from the principles of the invention and without sacrificing its chief advantages.

What I claim is:

1. In a tension device for tensioning the web as it is fed from a web roll to a printing press, the combination of means for rotatably supporting a web roll, a running belt driven from the press at a small fraction of the speed of the running web to be pressed against the surface of the web roll to exert a drag thereon, a counterbalanced pilot roller over which the web is fed normally urged by means of a resiliently suspended mass against the tension of the web looped around it, a brake restraining feeding movement of the running belt to vary the pressure of the belt against the web roll, and means for controlling the action of the brake on the running belt by the tension of the web as measured by the pilot roller.

2. A tension device as claimed in claim 1 in which snubbing means are provided acting on the mass to damp its motion.

3. A tension device as claimed in claim 1 in which there are provided a plurality of running belts each provided with a pilot-roller actuated brake and the brakes are interconnected for equalized actuation by the pilot roller.

4. In a web tension device to cooperate with a rotatably supported web roll feeding web to a printing press, the combination of a press-driven running belt to be pressed against the surface of the web roll, a brake restraining the free running of the belt, a pilot roller moved by changes in the tension of the web drawn from the web roll, a resiliently suspended mass tending to move the pilot roller as the web tension decreases and means controlling the action of the brake on the belt by movement of the pilot roller.

5. In a web tension device to cooperate with a rotatably supported web roll feeding web to a printing press, the combination of a plurality of press-driven running belts to be pressed into engagement with the surface of the web roll, individual brake means controlling the free running of the belts to control their pressure on the web roll and the web tension created thereby, flexible cable means interconnecting the several brake means for pressing the belts into contact with the web roll and for equalizing the action of the several belts on the web roll and for controlling the action of the several brakes.

6. A web tension device as claimed in claim 5 in which the cable is anchored at one of its ends by means of a weight having a normal position from which it may be freely lifted.

7. In a web tension device, the combination of means for rotatably supporting a web roll, a pilot roller moved by changes in the tension of a web fed to a printing press, brake means acting on the web roll for tensioning the web, said brake means comprising a rotatable brake drum, a pair of relatively movable brake shoes engageable with the brake drum, a weighted bell crank, a spring connecting the weighted bell crank with one of the brake shoes and forcing the shoe against the brake drum and means interconnecting the other brake shoe for movement by the pilot roller.

8. A tension device as claimed in claim 7 in which a pair of stops limit movement of the bell crank in either direction as it is moved by the pilot roller acting on the brake shoes.

9. In a web tension device for tensioning web as it is fed from a web roll to a printing press, the combination of means for rotatably supporting a web roll, a plurality of running belts to be pressed against the surface of the web roll to exert a drag thereon, the running belts being driven from the press at a fraction of the speed of the running web, a brake acting on each running belt to restrain its free running and to press the belt against the web roll surface, a weight normally actuating the brake, a pivotally mounted pilot roller moved by changes in web tension and about which the web is looped as it is fed to the press, a counterweight for balancing the pilot roller in its pivotal mounting, a resiliently suspended mass urging the pilot roller against the tension of the web, and means interconnecting the running belts with each other and with the pilot roller with the brake whereby the action of the weight on the brake may be varied by movement of the pilot roller in response to changes in the tension of the web.

10. A web tension device as claimed in claim 9 in which several brakes and running belts are provided, and a flexible cable forms the connec-

tion between the pilot roller and the several brakes, the cable is looped between guide pulleys over pulleys individually connected to the several brakes and the end of the cable away from the pilot roller is anchored to a weight which may be freely lifted.

11. In a tension device for tensioning the web as it is fed from a web roll to a printing press, the combination of means for rotatably supporting a web roll, a pair of spaced apart belt pulleys over which a belt runs in position to press against the surface of the web roll, one of said pulleys being driven at a small fraction of the surface speed of the web roll and in the same direction while web is fed to the press and the other being braked, means cooperating with the belt pulleys preventing slippage of the belt on the pulleys, and means for varying the braking force applied to the braked pulley whereby the pressure exerted by the belt against the web roll 20

is changed to vary the tension of the web fed from the web roll to the press.

12. A tension device as claimed in claim 11 in which the braked pulley cooperates with a pilot roller moved by changes in the tension of the web feed and the braking force on the pulley is varied by movement of the pilot roller.
